US0D1028522S

(12) **United States Design Patent** (10) Patent No.: **US D1,028,522 S**
Shen et al. (45) Date of Patent: ** May 28, 2024

(54) **CLEANING BRUSH**

- (71) Applicant: **Qinger Shen**, Zhangshu (CN)
(72) Inventors: **Qinger Shen**, Zhangshu (CN); **Cong Zhang**, Luohe (CN)
(73) Assignee: **Qinger Shen**, Zhangshu (CN)

(**) Term: **15 Years**

(21) Appl. No.: **29/914,819**

(22) Filed: **Oct. 23, 2023**

(51) LOC (14) Cl. **04-01**
(52) U.S. Cl.
USPC **D4/100**; D4/133

(57) **CLAIM**

The ornamental design for a cleaning brush, as shown and described.

DESCRIPTION

FIG. 1 is a front perspective view of a cleaning brush, showing my new design;

FIG. 2 is a rear perspective view thereof, shown in a position of use;

FIG. 3 is a front view FIG. 1;

FIG. 4 is a rear view thereof;

FIG. 5 is a left side view thereof;

FIG. 6 is a right side view thereof;

FIG. 7 is a top view thereof; and,

FIG. 8 is a bottom view.

The broken lines in the drawings illustrate the portions of the cleaning brush, which form no part of the claimed design.

1 Claim, 8 Drawing Sheets
